UNCURLING GUIDE FOR SEWING MACHINES

Walter Kneissler, Roselle, N. J., assignor to The Singer Manufacturing Company, Elizabeth, N. J., a corporation of New Jersey

Application July 23, 1942, Serial No. 451,999

7 Claims. (Cl. 112—20)

This invention relates to fabric uncurling and guiding devices and more particularly to that type of uncurling and guiding devices used on hosiery seaming machines.

The type of hosiery which is now in vogue has the heel and toe as well as the top or garter portions reenforced with additional interwoven threads, and thus it occurs that these sections of the hose are of heavier gage than the remaining sections. In the past, difficulty has been experienced in uncurling, guiding and seaming the edge portions of hosiery having a variable gage. Whenever the fabric changes from a heavy to a thin gage, while passing through an uncurler, the thin gage portion thereof tends to drop out of the uncurler as the heavy portion of the fabric has spread the uncurling wings of the uncurling guide away from the central fabric-guiding plate, so that they can not engage the thin fabric sections and hold them snugly against the fabric-guiding plate so that they will be held against dropping below the needle path. Among those skilled in the hosiery seaming art the above described difficulty is referred to as a "drop-out." Whenever the material thus drops below its normal level the needle will either miss the edge of the work or it will penetrate the work at a point so close to the edge that a weak seam will result.

It has been found that the above described "drop-outs" may be obviated if the work is raised slightly just before the relatively thick portion of the stocking terminates and the thin portion is encountered by the uncurler. Thus, by raising the work, the needle will be caused to penetrate the work at a substantial distance from the edge thereof. Also, it has been found that one of the most effective ways of raising the work is to provide an uncurling device which is free to rise in response to an upward force exerted by the free or unseamed portions of the work under skillful handling by the operator, thereby permitting the work to be fed to the feed cups at a higher level than normal.

It is therefore an object of present invention to provide a simple and inexpensive uncurling guide having at least a portion thereof shiftable in response to an upward force as exerted by the unseamed portions of the work.

With these and other objects in view, as will hereinafter appear, the invention consists in the devices, combinations and arrangements of parts described in connection with the accompanying drawing, which illustrates a preferred embodiment of the invention and in which—

Fig. 1 is a side elevation of the present invention.

Fig. 2 is a front elevation of the present invention as applied to a cup-feed hosiery seaming machine.

Fig. 3 is a disassembled perspective view of the main elements of the present invention.

Fig. 4 is a side elevation of the present invention as applied to a cup feed hosiery seaming machine with the outer feed-cup removed.

In the embodiment of the invention selected for illustration, my improved uncurling guide is shown as applied to a so-called cup-feed sewing machine having a standard 10 and an overhanging bracket 11 from which depends the uncurling guide and an outer feed cup 12. Co-operating with the outer feed-cup 12 is an inner feed-cup 13 for advancing the work past the stitching mechanism which includes a needle 14 and other devices not shown. For a detailed description of the cup-feed machine shown in the drawing, reference may be had to Patent No. 2,277,970, dated March 31, 1942, to Hans Hacklander.

Referring to Fig. 2 it will be observed that beneath the overhanging bracket 11 the machine frame is provided with a horizontal ledge 15 adapted to support for limited lateral adjustment a right-angle supporting bracket 16 to which is secured the uncurling guide. To provide for lateral adjustment of the guide, the horizontal limb of the right-angle bracket 16 is preferably formed with an elongated slot 17 through which passes a clamping screw 18 threaded into the ledge 15. The ledge 15 in its upper surface is formed with a guide-groove 19 which is adapted to receive a tongue 20 provided in the horizontal limb of the right-angle bracket 16.

Secured by a clamping screw 21 to the vertical limb of the right-angle bracket 16 which forms an uncurling guide plate, is the uncurling unit. Mounted upon the mid-portion of the screw 21 is a cylindrical boss 22 upon which is freely journaled the head 23 of the uncurling unit. The threaded end of the screw 21 is received in the stationary disk 24 which is drawn up and secured against the boss 22 which in turn is tightly forced up against the vertical limb of the bracket 16. The head 23, see Fig. 3, is formed with an apertured ear 25 into which is threaded a fulcrum-stud 26 upon which are journaled the latches 27 and 28 designed to lock the uncurling guide in operative or inoperative positions. The latches 27 and 28 and the above described pivotal support for the uncurling guide form no part of

the present invention, those parts being fully described in Patent No. 2,256,672, dated September 23, 1941, to Hans Hacklander.

The above noted uncurling unit comprises a head 23 provided with a vertically disposed cylindrical aperture 29 and a depending threaded pin 30. Adjustably secured to the head 23 is a fabric-guiding plate 31 provided with an upstanding guide pin 32 and an apertured boss 33 which slidily receives the depending pin 30. Together the head 23 and the fabric-guiding plate 31 form a two-part central plate. The guide pin 32 is slidily received within the aperture 29 and the top portion of the guide pin 32 is engaged by the lower end of a weak compression spring 34 which is disposed within the aperture 29. A set screw 35 threaded into the aperture 29 engages the upper end of the spring 34 to confine it within the aperture and to afford a means whereby the spring pressure may be varied, as by an adjustment of the screw 35. The spring 34 therefore, is effective to force the plate 31 downwardly and a thumb-nut 36 is threaded upon the lower end of the pin 30 so as to provide an adjustable stop means for determining the normal operating level or height of the guiding plate 31.

Secured to and disposed transversely of the plate 31 are two cross-bars 37 and 38 which are provided, respectively, with two threaded apertures 39 and two plain apertures 40 adapted to receive the threaded pins 41.

Cooperating with the plate 31 are two presser-members 42 pivotally secured thereto by means of the pins 41 passing through apertures 43 provided in said members. In the modification herein shown the guiding plate 31 terminates at its lower end in a fabric-guiding fin 44 and the presser-members 42 terminate in uncurling plates 45 which are urged toward the guide-fin 44 by means of the coil-spring 46. This spring 46 passes through the opening 47 provided in the head 23 to bear against the recessed bosses 48 of the presser-members 42.

Mounted within and transversely of the guide-fin 44 is a gauge pin 49 which extends from each face thereof to be received within each of the apertures 50 provided in the presser-members 42. Each uncurling plate 45 is formed with the usual uncurling protuberance 51 located upon the entrance end thereof.

Fig. 4 illustrates a hosiery blank 52 being delivered to the uncurler in the usual manner, and line 53 represents the normal level of the work. However, as hereinabove noted, it sometimes becomes desirable to increase the "bite" of the needle as by raising the normal feed level of the work. To raise the feed level, when using the present device, the operator need only raise the unseamed portion of the hosiery blank 52 and the upward force of edges of the hosiery blank upon the guide-pin 49 will in turn raise the uncurling unit against the action of the spring 34, which latter is weak enough to be overcome by such force. By adjusting the thumb-nut 36 the normal feed level of the work may be varied to suit the various sewing conditions.

Having thus set forth the nature of the invention, what I claim herein is:

1. A fabric uncurling and guiding device for sewing machines, comprising, a bracket member adapted to be secured to a sewing machine, a two-part central plate, one part of said central plate being pivotally secured to said bracket member, a pair of presser-members cooperating with and supported by the other part of said central

plate, and means connecting the two parts of said central plate together and permitting a limited amount of relative movement of said two parts toward and away from each other.

5 2. A fabric uncurling and guiding device for sewing machines, comprising, a two-part central plate, means pivotally supporting one part of said central plate, a pair of presser-members cooperating with and supported by the other part of said central plate, one of said two parts being provided with an aperture and the other being provided with a pin slidily received within said aperture, a spring associated with said two parts so as to urge them in opposite directions, and 10 means to limit the relative movement of said two parts toward and away from each other.

3. A fabric uncurling and guiding device for sewing machines, comprising, a two-part central plate, means supporting one part of said central plate, a pair of presser-members cooperating with and supported by the other part of said central plate, said two parts being provided with a pair of pins and a pair of apertures arranged to slidily receive said pins, an element carried by one 15 of said pins for limiting relative movement between said two parts, and a spring disposed within one of said apertures and engaging one of said pins to spring bias said two parts in opposite directions.

30 4. A fabric uncurling and guiding device for sewing machines, comprising, a head member, means to pivotally secure said head member upon said sewing machine, a fabric-guiding plate, a pair of presser-members cooperating with and supported entirely by said fabric-guiding plate, and means connecting said fabric-guiding plate and said head member and permitting a limited amount of relative movement of said two parts toward and away from each other.

35 5. A fabric uncurling and guiding device for sewing machines, comprising, a head member, means to pivotally secure said head member upon said sewing machine, a fabric-guiding plate, a pair of presser members cooperating with and supported entirely by said fabric-guiding plate, means connecting said fabric-guiding plate and said head member and permitting said fabric-guiding plate to be moved toward and from said head member, a spring element associated with said fabric-guiding plate to spring bias the same away from said supporting member, and means carried by said head member for limiting the amount of movement of said fabric-guiding plate relative to said head member.

55 6. A fabric uncurling and guiding device for sewing machines, comprising, a head member, means to pivotally secure said head member upon said sewing machine, a fabric-guiding plate carried entirely by said head member, a pair of presser-members carried by said guiding plate for cooperating with the opposite sides thereof in the uncurling and guiding of a fabric, a spring interposed between said head member and said fabric-guiding plate for spring biasing the latter away from said head member, a gauging pin carried by said fabric-guiding plate for contacting and gauging the height of a fabric edge, and means connecting said head member and said fabric-guiding plate and permitting relative rectilinear movement between said two elements against the action of said spring whenever the fabric edge is forcefully urged against said gauging pin and toward said head member.

70 7. A fabric uncurling and guiding device for sewing machines having a pair of horizontally

disposed feeding-cups, said device comprising a head member, means to pivotally secure said head member upon said sewing machine at a point above said feeding-cups, a fabric-guiding plate carried entirely by said head member and depending therefrom to be disposed substantially between said head member and the plane containing said feeding-cups, a plurality of uncurling elements carried by said fabric-guiding plate, a

spring element disposed between said head member and said fabric-guiding plate for spring biasing the latter element away from said head member, and means connecting said head member and said fabric-guiding plate so as to permit the latter element to be moved upwardly toward said head member against the action of said spring.

WALTER KNEISSLER.
